William Reiff William

UNITED STATES PATENT OFFICE.

AARON GROFF, OF ST. PAUL, MINNESOTA.

FOLDED PAPER NAPKIN.

Application filed December 21, 1925. Serial No. 76,677.

This invention relates to a folded article of thin sheet material, such as paper, and particularly relates to a folded paper napkin. Paper napkins are now used in this country at the rate of about fifty million a day and the making and folding of these napkins is quite a large business. The napkins are usually folded and packed in boxes in which they are shipped to the customer. It is desirable, therefore, to have the napkins folded into efficient shape and one which will economically lend itself to packing.

The napkins are largely used in restaurants and lunch rooms and the same are often placed, side by side, in a container. It is desirable, therefore, to have the napkins so folded that it will be easy to select one napkin from the group. With napkins folded, as heretofore, it often happens that a patron will take two or three napkins out of the container, intending only to take one and said two or three napkins are usually then used and rendered unfit for further use.

It is an object of this invention, therefore, to provide a folded napkin folded into very convenient form for use and so that it can readily be economically packed and also can readily be selected from a group of napkins in the container.

It is a further object of the invention to provide a napkin of rectangular shape folded into substantially triangular form, the napkins first being folded into quarters and then having its side portions folded onto opposite sides of a central portion.

It is still further an object of the invention to provide a folded napkin, as set forth in the preceding paragraph, in which the central portion has a pointed end projecting beyond the folded side portions, which end portion is then folded over toward said side portions.

It is more specifically an object of the invention to provide a napkin of rectangular form folded successively to quarter size and then having side portions substantially triangular in shape folded onto opposite sides of the central portion to form a folded article pointed at one end and having a projecting triangular portion at its opposite end, which triangular portion is then folded toward the pointed end.

It is also an object of the invention to pro-

vide a novel method of folding a paper napkin.

These and other objects and advantages of the invention will be fully set forth in the following description made in connection with the accompanying drawings in which like reference characters refer to the same parts throughout the different views, and in which,

Fig. 1 is a plan view of a napkin used having dotted lines thereon indicating lines along which the napkin is folded in one method of folding disclosed herein;

Fig. 2 is a plan view of a napkin in folded condition;

Fig. 3 is a vertical section taken on the line 3—3 of Fig. 2, as indicated by the arrows;

Fig. 4 is a plan view of the folded napkin folded in slightly different manner than that shown in Fig. 2;

Fig. 5 is a vertical section taken on the line 5—5 of Fig. 4, as indicated by the arrows;

Fig. 6 is a plan view of a napkin folded in modified form; and

Fig. 7 is a view illustrating how the napkins may be packed.

Referring to the drawings, in Fig. 1 a napkin 10 is illustrated, and while the napkin may be made in various shapes, in the embodiment of the invention illustrated, the same is shown of rectangular shape, preferably substantially square. The napkin is first folded into quarters, and while this may be variously done, in the embodiment of the invention illustrated, the napkin is shown as being successively folded along median lines 10^a and 10^b. The napkin is thus brought into multiple ply form having a size or area one-quarter of its original area. In the form shown in Fig. 2, the napkin has a side portion 10^c folded inwardly toward a central portion 10^d along a line 10^e extending substantially from one corner of the quarter size folded napkin to an intermediate point in one of the sides forming the opposite corner. Another side portion 10^f similar to the side portion 10^c is now folded inwardly along the line 10^g which also extends from one corner of the quarter

multi-ply articles to an intermediate point in the other side forming the opposite corner. The side 10^f is folded to lie down upon

the opposite side of the central portion 10^a from the side portion 10^e, as shown in Fig. 3. After the side portions 10^e and 10^f have been folded, as described, the central portion has a pointed end portion 10^h at its end opposite the corner from which lines 10^e and 10^g extend, and this pointed or triangular end portion is then folded inwardly substantially along the line 10ⁱ connecting the points at which the lines 10^e and 10^g intersect the sides of the article, which line extends substantially perpendicular to the diagonal extending from the corner at which lines 10^e and 10^g intersect. It will be seen that the free and longer edge of the side portion 10^e and 10^f are spaced by small angles from the sides of the central portion, respectively. The side portions 10^e and 10^f and the central portion 10^a all have pointed ends meeting in a substantially common point but the angle of the sides of the central portion is somewhat greater than the angles between the sides of the side portions. The completed folded napkin, as shown in Fig. 2, is then of substantially triangular form. Such a folded napkin readily lends itself to economical packing. The folded napkins can be placed in reverse arrangement, as shown in Fig. 7, and thus economically packed in a box.

When such a napkin, as shown in Fig. 2 is placed in an open top container in groups, it will be very easy to select one of the napkins from the group. There will always be one of the side edges of the side portions 10^e or 10^f at the outer side of the group which can be grasped between the fingers of the person selecting the napkin. It will thus be insured that only one napkin will be selected. If the folded-over end portion should be on the outside of the group the person selecting the napkin could also draw out from the pile by grasping the said end portion between his fingers. The napkins can very readily be opened for use by the patron by merely taking hold of the edges of the side portions 10^e and 10^f and then opening the napkin.

In Fig. 4, a slightly modified form of folding is shown. The napkin is folded into quarters, as already described, and the side portions 10^e and 10^f are then folded inwardly. Instead of folding one side portion at one side of the central portion, however, and the other side portion at the opposite side of the central portion, both side portions 10^e and 10^f are folded down at the same side of the central portion, the side portion 10^e being superposed on the side portion 10^f. The end portion 10^h is then folded over, as already described. The napkin folded, as shown in Fig. 4, may also be very economically packed. When the same is placed in a container for use, however, it may happen that there will be no free edge of the side

portion on the exterior of the group of napkins. The form shown in Fig. 4 may be preferred by some factories having machines already built for folding the side portions 10^e and 10^f onto one side of the central portion, it then being only necessary to turn over the end portion 10^h.

In Fig. 6 the napkin is folded, as already described in connection with Figs. 2 and 3, except that the end portion 10^j, instead of being folded inwardly substantially along the line 10ⁱ, has its end portion 10^j folded along a line parallel to the line 10ⁱ and substantially midway between the line 10ⁱ and the adjacent corner or tip of the pointed end. The advantage in the form shown in Fig. 6 is that in the complete folded napkin there will be no additional thickness under folded end 10^j as there is at the zone where the folded-over portion 10^h overlies both of the side portions 10^e and 10^f. When the napkins are packed, one on top of the other in the box, more of the napkins can thus be placed in the box. At the same time, the folded-over end portion 10^j saves considerable in the area of the box used. The napkin shown in Fig. 6 has all the advantages in use already set forth in connection with the napkin shown in Figs. 2 and 3.

The folded napkins are now often placed in a so-called sanitary container. This container is in the shape of an inverted trough with its side arranged approximately to fit the folded napkin, said sides being disposed at an angle to each other substantially the same as the angle between the sides of the folded napkin, as shown in Figs. 2 and 4. The container is open at one end and has flanges at said end extending partially across the end napkin, the napkins usually being held therein against said flanges by a resiliently moved plate. With such containers it is difficult to remove one napkin when the napkins are folded as heretofore with the ends projecting straight. With a napkin folded as disclosed in the present application, that is, with the end portions 10^h and 10^j folded over, it is an easy matter for the napkin to be removed. The folded-over end will be at the open end of the container and the same can always be grasped at a point between the side flanges of the container. The customer is therefore sure to remove only one napkin and the napkin can be readily grasped by the fingers for such removal.

From the above description it will be seen that applicant has provided a greatly improved folded napkin and method of folding the same. The space necessary for packing the napkins is greatly reduced and the napkins have distinct advantages in use. As above stated, the number of napkins used daily in this country is very large and the provision of napkins is quite an item of ex-

pense in the conduct of eating places. The use of paper napkins in homes and domestic establishments is largely on the increase as well. The folded napkins disclosed herein has been amply demonstrated in actual use and found to be very successful and efficient.

It will, of course, be understood, that various changes may be made in the form, details, arrangement and proportions of the parts and in the steps and sequence of steps in the method without departing from the scope of applicant's invention, which, generally stated, consists in a device capable of carrying out the objects above set forth, in the novel method, parts and combinations of parts disclosed and defined in the appended claims.

What is claimed is:

1. A folded article comprising a substantially rectangular paper sheet folded successively on its two median lines into a fourply rectangular article and further having its side portions folded inwardly to lie at opposite sides of its central portion along lines extending substantially from one folded corner to intermediate points on the sides forming the opposite corner, thus producing an article having a point at the free edges of said plies, said article having the said point folded over on a line, normal to the median line thereof, and disposed between the point occupied by the tip of said point

before said point was folded over and the line joining said intermediate points.

2. A folded article comprising a substantially rectangular paper sheet folded successively on its two median lines into a fourply rectangular article, and further having its side portions folded inwardly so that the side portions and the central portion lie in juxtaposition thus producing an article having a point at its end, said article having the said point folded over on a line substantially normal to the median line thereof and disposed between the point occupied by the tip of said point before being folded over and the line joining said intermediate points.

3. A folded article comprising a substantially rectangular paper sheet folded successively on its two median lines into a fourply rectangular article and further folded inwardly to lie at opposite sides of its central portion, said side portions being folded along lines extending substantially from one corner of said article to intermediate points on the sides forming the opposite corner, thus forming an article having a point at its end, whereby an edge is disposed at each side of said napkin which can be engaged to withdraw said napkin from a stack of napkins or from a container.

In testimony whereof I affix my signature.

AARON GROFF.
